UNITED STATES PATENT OFFICE.

FRANK H. STETSON, OF LAWRENCE, MASSACHUSETTS.

LOOM-SHUTTLE.

SPECIFICATION forming part of Letters Patent No. 375,104, dated December 20, 1887.

Application filed December 20, 1886. Serial No. 222,049. (No model.)

To all whom it may concern:

Be it known that I, FRANK H. STETSON, of Lawrence, in the county of Essex and State of Massachusetts, a citizen of the United States, 5 have invented a new and useful Improvement in Loom-Shuttles, of which the following is a full, clear, and exact description, reference being had to the accompanying drawings, forming a part of this specification, in explaining 10 its nature.

The invention relates to a shuttle having a spindle especially designed for holding worsted bobbins; and it comprises a spindle made in two longitudinal sections, one of which is permanently hinged to the base or rear end of the shuttle and the other of which is adapted to be held thereto, when the spindle is in operative position, at its butt-end by means of a bar or stud, which extends across the spindle-cavity close to the hinge, and the spring which holds the spindle in its straight position in the shuttle-cavity, and at its front end by engagement with the front end of the hinged member of the spindle.

25 Referring to the drawings, Figure 1 is a vertical longitudinal section of a shuttle having the features of my invention. Fig. 2 is a longitudinal section showing the same parts as shown in Fig. 1, but in a different position. 30 Fig. 3 is a view of the two parts of the spindle removed from the shuttle. Fig. 4 is a view of the same parts, showing a slight modification. Fig. 5 is a detail view. Fig. 6 is a cross-section of the divided spindle on the line indicated by the dotted arrow in Fig. 3.

35 A is the shuttle-body.

a is the cavity.

B is the section or part of the spindle which is hinged or pivoted by the pivot b to the shuttle-body.

40 C is the removable section of the spindle. The part B has at its base or inner end the extensions or plates b' b'', which are substantially parallel with each other in the direction of their length, and which form between them a dovetail holding recess or cavity, b³, for the reception of the butt-end of the other section or part of the spindle. These plates or projections each have a cross notch or groove, b⁴, 45 which is formed to be in line with the stud or pin b⁵ when the spindle is in operative posi-

tion. The removable section of the spindle has its butt or inner end, c, shaped to fit the dovetail recess or cavity b³ and the cross groove or notch c', which receives or is moved upon the cross-stud b⁵ when the spindle is moved to its operative position. The hinged section B has the flat surface b⁶, the curved surface b⁷, and is somewhat shorter from its shoulder b⁸ to its end than the full length of the complete 60 spindle. The removable section C has the flat surface c², which fits the flat surface of the hinged section, the curved surface c³, and the full section or end c⁴, to the end of which the button or disk c⁵ is fastened, and the outer end 65 of the hinged section is attached to the outer end of the removable section in any desired way. I have shown in the drawings two methods of attachment.

In Fig. 3 the hinged member is represented 70 as provided with a short pin or reduced section, b⁹, at its end, which fits the hole c⁶, formed in the full part of the removable section of the spindle.

In Fig. 4 I have shown the outer end of the 75 hinged section as cut away or tapered to form an extension which shall enter a recess of corresponding shape formed in the full end of the detachable section. The first-named construction I consider preferable. There are other 80 ways by which the outer ends may be secured, and I would not confine myself to the especial form herein mentioned.

In use the detachable section of the spindle is slipped through the bobbin-hole until the 85 disk or button bears against the outer end of the bobbin. This brings the butt or inner end of the removable section beyond the butt of the bobbin. The flat surface of this inner end is then placed upon the flat surface of the 90 hinged section of the spindle, and the bobbin and detachable section are moved thereon until the butt of the detachable section enters the dovetail cavity or hole at the butt of the hinged section, and the reduced section or end 95 of the hinged section enters the hole or cavity in the end of the detachable section, and the bobbin is confined between the button or disk c⁵ and the base-shoulder b⁸ of the spindle. The spindle is then moved into the shuttle-cavity, 100 and the spring D serves to hold or maintain it in the cavity, and the two sections of the

spindle are locked together by the cross-stud, so that endwise movement of the movable section of the spindle in relation to the fixed section cannot take place while the spindle is in this position.

It will be seen that this construction affords a very simple way of placing and removing the bobbin, and that the button or disk serves not only to hold the bobbin upon the spindle, but also as a guide over which the yarn is drawn from the cop.

It will be seen that by the use of a spindle of this construction, having the disk or button c' , there is a very even tension upon the yarn 15 in weaving from the bobbin or cop as the yarn passes over a guiding surface, which is always of the same size; also, that the disk serves to permit the use of split or cracked bobbins, because it serves to hold the yarn away from 20 the edge of the bobbin, being always larger than the end of the bobbin.

I would say that I do not confine the invention to its use with worsted bobbins, but may employ it for any purpose where a divided 25 spindle with an end disk can be used for the purpose of holding a spool, bobbin, or cop in a shuttle.

Having thus fully described my invention, I claim and desire to secure by Letters Patent 30 of the United States—

1. The combination, with a shuttle-body, of a longitudinally-divided spindle, the two parts of which are connected together at or near their opposite ends to prevent lateral displacement, the removable part of the said spindle being provided with a disk or button, substantially as set forth.

2. The combination, with a shuttle-body, of a longitudinally-divided spindle, one part of 40 which is attached to the said body and is provided at its butt-end with a holding-recess, the other or removable part of the said spindle being provided at its outer or free end with a disk or button and having its inner or butt 45 end fitted to fill the said holding-recess, substantially as set forth.

3. The combination of a shuttle-body with a two-partspindle, one of which parts is hinged to the shuttle-body and has the plates b' b^2 and cross notches or grooves b^4 , and the other of 50 which has an end section having a cross groove or notch, c' , and is adapted to fit the space between the said plates and the locking-bar b^5 , substantially as described.

4. The combination, with the shuttle-body, 55 of a longitudinally-divided spindle, one part of which is hinged to the said body and is provided at its butt with a dovetailed holding-recess, the other or removable part of the said spindle having its butt-end fitted to the 60 said dovetailed recess and being provided at its outer or free end with a disk or button, substantially as set forth.

5. The combination, with a shuttle-body and a longitudinally-divided spindle, one part of 65 which is provided at its butt with a holding-recess and the other part of which has a butt fitting the said recess, of the cross-stud or locking-bar b^5 and the spring D, substantially as set forth.

6. The combination, with a shuttle-body, of a longitudinally-divided spindle consisting of the sections or parts B and C, the part B having its outer end reduced and being provided at its butt or hinged end with a holding-recess, and the part C having near its outer end 75 a hole or cavity for the reception of the said reduced end and having its butt-end fitted to fill the said holding-recess, substantially as set forth.

7. The combination of the shuttle-body with a spindle made in two longitudinal parts, one of which is hinged to the spindle-body and the other of which is removably attached at its butt and point ends to the hinged part of the 8; spindle, and a disk or button secured to the end of the removable part, substantially as described.

FRANK H. STETSON.
